US00D673280S

(12) **United States Design Patent**
Einarsson

(10) **Patent No.:** **US D673,280 S**
(45) **Date of Patent:** **** Dec. 25, 2012**

(54) **ORTHOPEDIC DEVICE**

4,651,726 A 3/1987 Holland
4,724,847 A 2/1988 Nelson
4,825,856 A 5/1989 Nelson
(Continued)

(75) Inventor: **Palmi Einarsson**, San Juan Capistrano, CA (US)

(73) Assignee: **OSSUR HF**, Reykjavik (IS)

(**) Term: **14 Years**

(21) Appl. No.: **29/363,315**

(22) Filed: **Jun. 8, 2010**

Related U.S. Application Data

(62) Division of application No. 29/343,468, filed on Sep. 14, 2009, now Pat. No. Des. 620,124.

(57) **CLAIM**

The ornamental design for an orthopedic device, as shown and described.

DESCRIPTION

FIG. 1 is a first perspective view of the orthopedic device shown in an open configuration

FIG. 2 is a second perspective view of the orthopedic device according to FIG. 1.

FIG. 3 is a front elevational view according to FIG. 1.

FIG. 4 is a rear elevational view according to FIG. 1.

FIG. 5 is a first side elevational view according to FIG. 1.

FIG. 6 is a second side elevational view according to FIG. 1.

FIG. 7 is a top plan view according to FIG. 1; and,

FIG. 8 is a bottom plan view according to FIG. 1.

The broken lines illustrate environmental supplementary structure of the orthopedic device and form no part of the claimed design.

1 Claim, 8 Drawing Sheets
